United States Patent Office

Des. 188,065
Patented May 31, 1960

188,065

RECEPTACLE HANDLE

James L. Hvale, Chicago, Ill., assignor to Ekco Products Company, Chicago, Ill., a corporation of Illinois

Filed Sept. 19, 1958, Ser. No. 52,597

Term of patent 14 years

(Cl. D44—29)

Fig. 1 is a top plan view of a side handle for cooking utensils and the like, showing my new design.

Fig. 2 is a side elevational view thereof.

Fig. 3 is a left end elevation view thereof.

Fig. 4 is a bottom plan view thereof.

Fig. 5 is a fragmentary section taken on line 5—5 of Fig. 1.

I claim:

The ornamental design for a side handle for cooking utensils and the like, as shown.
